APPARATUS AND METHOD FOR CONTROLLING REFRIGERATION

Earnest J. Dillman, Detroit, Mich., assignor to
Detroit Lubricator Company, Detroit, Mich., a
Corporation of Michigan

Application October 14, 1931, Serial No. 568,664

16 Claims. (Cl. 62—2)

My invention relates to new and useful improvements in the method and apparatus for controlling the evaporation of a refrigerant medium in the evaporator of a refrigerating system.

5 My method of controlling the evaporation of refrigerant medium in an evaporator contemplates the maintenance of a substantially constant difference between the temperature of the refrigerant medium in the evaporator and the 10 temperature of the return or suction line at a point closely adjacent the evaporator. By maintaining a substantially constant temperature differential, the evaporator may be operated at its maximum capacity and therefore the system embodying the evaporator will be maintained at 15 maximum efficiency. Should the temperature differential decrease substantially below that at which maximum capacity is obtained, then liquid refrigerant is liable to enter the return or suction line and be drawn back to the compressor. More particularly my method contemplates controlling the admission of the refrigerant medium to the evaporator in accordance with the 20 maintenance of a substantially constant temperature differential, so that the temperature differential 25 will be maintained substantially constant by the controlled evaporation of the admitted refrigerant medium.

The invention consists in the method and the 30 apparatus for carrying the same into effect, to be more fully described hereinafter, and the novelty of which will be particularly pointed out and distinctly claimed.

In the accompanying drawing, to be taken as 35 a part of this specification, I have fully and clearly illustrated one embodiment of my invention, in which drawing—

Figure 1 is a diagrammatic view of a refrigerating system embodying my invention, and

40 Fig. 2 is a view in longitudinal, central section of a valve employed in the system.

Referring to the drawing by characters of reference, 1 designates an evaporator or cooling element which may be of the coil type, having a refrigerant medium supply or feed line or conduit 2 and a return or suction line or conduit 3. The supply line 2 leads from a receiver 4 fed by a condenser 5 connected to the outlet or discharge side of a compressor 6 to the inlet of which the return line 3 leads and is connected. The compressor may be driven by an electric motor 7 having the usual condenser cooling fan (not shown). The motor is controlled by a pressure switch 8 responsive to variation in pressure in the return line 3 and connected in series circuit

in the electric leads 9, 10 of the motor, thereby to start and stop the motor and therefore the compressor at predetermined desired refrigerant medium pressure limits. In the supply conduit 2 is a valve means 11 which controls the admission of refrigerant medium to the evaporator 1. 5

This valve means 11 is shown in detail in Fig. 2, and comprises a thermostatic expansion valve having a temperature responsive bulb 12 containing or charged with a volatile fluid such as methyl 10 chloride, and which is rigidly secured by clamping means 13 in intimate heat conducting relation to the refrigerant medium return line 3 at a point closely adjacent the evaporator and as near thereto as practicable. The bulb 12 is connected by a conduit or tube 14 to the interior of a chambered element 15 which is rigidly supported by and preferably a part of the valve means 11. The element 15 comprises an actuating member or power element having a movable 15 head or wall 16 which is hermetically secured and sealed at its periphery to one end of an expandable-collapsible element 17, such as a circumferentially corrugated, substantially cylindrical, resilient, metallic bellows having its other end 20 closed and sealed to the periphery of a plate or supporting member 18 which is apertured to receive the conduit or tube 14 to which the member 18 is rigidly secured and sealed, as at 19. The end of tube 14 has fixed thereto a guide member 30 or sleeve 20 which is reciprocably supported in the bore of a plug member 21 fixed in a central aperture in the base of a cap member 22. The plug member 21 is externally and internally threaded outside the cap member to receive an 35 adjustment nut 23 through which tube 14 extends, and which is threaded into the bore of member 21, and also to receive an external packing nut 24 to retain packing 25 in position to prevent flow through the plug bore around nut 23. 40 Within the element 15 is an expansion member 26, preferably a coil spring under compression and acting to expand the bellows and maintain sleeve 20 in engagement with adjustment nut 23. The head 16 is preferably indented or concave inwardly at its center portion to retain one end of spring 26 in position, the other end of the spring being positioned by the plate member 18 and sleeve 20. The cap member 22 is seated on and sealed to a hollow supporting member 27 which 45 is of insulating material such as bakelite. Within the member 27 is a transverse partition 28 having a central guide aperture 29 aligned with the indentation in the bellows head and for a purpose 50 to be described. The member 27 is mounted on 55

a valve casing or body 30 and is secured and sealed to a continuous flange or extension 31, preferably cylindrical, on the valve casing. Secured and hermetically sealed to the flange 31 is a pressure responsive means, including an expandable-collapsible member 32 such as a circumferentially corrugated, substantially cylindrical, resilient, metallic bellows which extends into the hollow supporting member 27. Secured and hermetically sealed to the free end of the bellows is a substantially cup-shaped head or end wall 33 which extends longitudinally through the bellows into the valve casing, and which carries a yoke member or arm 34 fixed thereto by means of a post 35 extending through aligned apertures in the head 33 and member 34. The post 35 has a flange 36 which seats on the head 33 and is sealed thereto by solder or the like to prevent leakage from the casing around the post. Screw-threaded on the post within the cup-shaped head is a sleeve member 37 having a lateral flange 38 at its free end against which abuts one end of a coil spring 39 surrounding the sleeve member. The other end of the spring 39 seats on a supporting member 40 mounted on the end of flange 31, such that the spring 39 is held under compression against the flange 38 and normally tends to expand the bellows 32. The top end of post 35 is recessed to receive one end of a thrust rod or member 41 which extends through the guide aperture 29, and which seats at its other end in the indentation or concavity in the bellows head 16. Within the valve casing is a boss or extension 42 extending transversely to the longitudinal axis of rod 41 and having an inlet passage 43 opening into said casing on the opposite side from said rod and provided with a valve guide and seat member 44. Reciprocable in the guide and cooperable with the valve seat 45 is a valve 45, preferably of the needle type, which is supported by and secured to the free end of the yoke member 34 which extends around the extension 42. In the passage 43 is a strainer member 46 secured in position by a nipple 47 which is secured and connected to the supply conduit 2. The casing has an outlet 48 communicating with the interior of bellows 32 and connected by a nipple or the like (not shown) to the evaporator inlet.

The operation of the system is as follows: With a temperature differential of eleven and one-half degrees Fahrenheit between the temperature of evaporation of the refrigerant medium in the evaporator and the temperature of the return or suction line at the evaporator, the evaporator will be operating at maximum capacity. By maintaining this temperature differential for all evaporator temperatures, the evaporator will be maintained at maximum capacity and the system at maximum efficiency. This temperature differential may be maintained by controlling the admission of refrigerant medium to the evaporator in accordance with the maintenance of the predetermined differential. If, for example, the refrigerant medium employed is methyl chloride, then with evaporation of the refrigerant medium in the evaporator occurring at say, 13.5° F., the evaporator will be at maximum capacity when the temperature of the return line at a point near the evaporator is 25° F. At these temperatures the valve 45 should be seated or closed with the force tending to open the valve balancing the force tending to close the valve, so that if there is any increase in the temperature of the return line, and therefore of the bulb 12, at the evaporator, or if there is any decrease in the temperature of evaporation within the evaporator, the valve 45 will be opened to admit refrigerant medium to the evaporator and maintain the desired differential. In order to maintain this differential for all operating temperatures of the evaporator, the change in force exerted by the power element 15 for each degree change of temperature must be less than the change in force exerted by the bellows 32 for each degree change of temperature, and if, for example, the ratio in square inches of the effective areas of the element 15 and the bellows 32 is as 1.00 to 1.16, then the desired temperature differential will be maintained for methyl chloride refrigerant. The pressure or force exerted by the element 15 at a bulb temperature of 25° F. will be for methyl chloride 17.5 pounds, as the effective area of element 15 is unity, and the force exerted by the bellows 32 will be in accordance with the temperature of evaporation of the refrigerant in the evaporator, which at 13.5° F. is 10.5 pounds per square inch for methyl chloride, so that the force exerted by bellows 32 tending to close the valve 45 will be 12.18 pounds. Therefore in order to have the valve in balanced closed position, the springs 26 and 39 are adjusted by the nut 23 to exert a resultant force equal to the difference between the opposing forces, namely, a force of 5.32 pounds acting to seat the valve. When the system is started in operation from a warm condition by closing of the circuit of motor 7, with the temperature of the bulb 12 at say, 80° F., the force exerted by the power element 15 will be 71.75 pounds acting through rod 41 and tending to open the valve 45. In order that the evaporator may be operating at maximum capacity at this starting temperature, there should be a differential of 11.5° F. or the temperature in the evaporator should be 68.5° F., which corresponds to a refrigerant medium pressure with methyl chloride of 57.2 pounds per square inch. This force acting through the bellows 32 to close valve 45 will, due to the effective area of bellows 32, be exerting a force on rod 41 of 66.43 pounds, which added to the force exerted by the springs 26 and 39 of 5.32 pounds equals 71.75 pounds, so that the valve is held in balanced closed position. When the compressor reduces the pressure in the evaporator below 57.2 pounds per square inch, the power element 15 being subject to a temperature of 80° F. will act to open valve 45 to admit refrigerant medium to the evaporator, the medium expanding therein to increase the pressure and close the valve. This will, however, decrease the temperature of the return line and therefore of the bulb, so that the pressure in the evaporator may be further reduced by the compressor before the valve 45 will be opened. This gradual step by step reduction of pressure while maintaining a substantially constant temperature differential will continue until the low pressure limit is reached, corresponding to a temperature of, say, 25° F. at the bulb 12, when the switch 8 will stop the motor and compressor. As the bulb 12 warms, tending to open valve 45, the refrigerant medium in the evaporator will also expand to increase the evaporator pressure which acting through bellows 32 will prevent the valve from opening. The temperature of the evaporator increases until the predetermined desired maximum pressure in the return line is reached, when switch 8 will again turn on the motor 7 to complete a cycle of operation and start a decrease of evaporator temperature.

From the foregoing, it is apparent that the valve means 11 operates to maintain a constant temperature differential between the temperature of the refrigerant medium in the evaporator and the temperature of the return line at the evaporator, so that the evaporator is maintained at maximum operating capacity, regardless of the temperature in the evaporator.

It is also to be noted that the number of degrees difference, or the temperature differential, may be increased by an increase in the above ratio of effective bellows areas, and may be decreased by a decrease in the said ratio.

What I claim and desire to secure by Letters Patent of the United States is:

1. A device of the character described, comprising a valve casing having an inlet and an outlet, a valve in said casing operable to control flow therethrough, means normally acting to move said valve toward closed position, an expansible-collapsible member operatively connected to said valve and acting upon increase of pressure in said casing to urge said valve toward closed position, temperature responsive means including an expansible-collapsible member, and a thrust member positively held in engagement with said last-named member and said valve and operable upon increase of temperature to urge said valve toward open position, said last-named expansible-collapsible member being of less effective cross-sectional area than said first-named expansible-collapsible member.

2. A device of the character described, comprising a valve casing having an inlet and an outlet, a valve in said casing operable to control flow therethrough, an expansible-collapsible bellows member closing and sealing a portion of said casing and having operative connection to said valve, said member being responsive to pressure in said casing, temperature responsive means including an expansible-collapsible bellows member and containing a volatile fluid responsive to variations in temperature, and a thrust member resiliently held in engagement with and between said second-named bellows member and said valve and operable to transmit movement of said second-named bellows member in response to temperature increase to said valve, said second-named bellows member being of less effective cross-sectional area than said first-named bellows member whereby said valve will be controlled by a substantially constant temperature differential.

3. The method of operating a refrigerating system which comprises regulating the rate of admission of refrigerant to the evaporator in accordance with both variation of temperature in the evaporator and variation of temperature at a given point in the return or suction line from the evaporator and maintaining substantially constant the difference between the temperature in the evaporator and the temperature at said given point so that the system will be kept at maximum operating capacity.

4. The method of operating a refrigerating system which comprises decreasing the temperature of the evaporator at a substantially constant rate while maintaining a predetermined constant temperature differential between the temperature of the refrigerant in the evaporator and the temperature of the return or suction line adjacent the evaporator, and regulating the rate of admission of refrigerant to the evaporator in accordance with and dependent on both variation of refrigerant temperature in the evaporator and varia-

tion of return line temperature adjacent the evaporator throughout the range of temperature decrease whereby to maintain the evaporator wet throughout its internal length and to obtain the maximum operating capacity of the system.

5. A device for maintaining in a refrigerating system a substantially constant temperature differential between the temperature of the refrigerant in the evaporator and the temperature of the refrigerant return or suction line adjacent the evaporator which comprises an automatically operable valve controlling admission of refrigerant to the evaporator, a pressure operated element responsive to and exerting a force in accordance with the temperature of the refrigerant return line, a pressure operated element responsive to and exerting a force in accordance with the temperature of the refrigerant in the evaporator, a thrust member for transmitting the force of said first-named element to said second-named element, means for transmitting the forces exerted by said first-named and said second-named elements to said valve, said second-named element having a greater effective pressure responsive area than said first-named element whereby said second-named element will exert a greater force than said first-named element for a given refrigerant temperature thereby to compensate for increase in pressure difference of the refrigerant for a given temperature difference of the refrigerant as the temperature of the refrigerant increases.

6. A device of the character described, comprising a valve casing having an inlet and an outlet and containing a valve port, a valve member cooperable with said port, a pressure responsive element movable in response to change of pressure in said casing and operatively connected to said valve member, said casing having a hollow extension surrounding said element and having a guide aperture, a cap member secured on said extension, an expansible-collapsible casing positioned within and spaced from the side walls of said cap member, a thrust member extending through said aperture and positioned between and at one end engaging said expansible-collapsible casing and at its other end engaging said element, and a coil spring surrounding said thrust member and acting through said thrust member to oppose expansion of said expansible-collapsible casing.

7. A device of the character described, comprising a valve casing having an inlet and an outlet and containing a valve port, a valve member cooperable with said port, a pressure responsive element movable in response to change of pressure in said casing and operatively connected to said valve member, a hollow member secured on said casing and overlying said element, said hollow member having guide means, an expansible-collapsible casing within said hollow member, a tubular member projecting from said expansible-collapsible casing and reciprocable in said guide means, an adjustment member carried by said hollow member and engaging said tubular member to adjust said expansible-collapsible casing, a bulb element having conduit means opening into said expansible-collapsible casing through said tubular member, and a thrust member operatively connecting said expansible-collapsible casing and said valve member.

8. A device of the character described, comprising a valve casing having an inlet and an outlet and containing a valve port, a valve member

- cooperable with said port, a pressure responsive element movable in response to change of pressure in said casing and operatively connected to said valve member, a hollow member secured on 5 said casing and overlying said element, said hollow member having guide means, an expansible-collapsible casing within said hollow member, a tubular member projecting from said expansible-collapsible casing and reciprocable in said guide 10 means, an adjustment member carried by said hollow member and engaging said tubular member to adjust said expansible-collapsible casing, a helical coil spring within said expansible-collapsible casing and urging said tubular member 15 into engagement with said adjustment member, a bulb element having conduit means opening into said expansible-collapsible casing through said tubular member, and a thrust member operatively connecting said expansible-collapsible casing and said valve member. 20
9. A device of the character described, comprising a valve casing having an inlet and an outlet and containing a valve port, a valve member cooperable with said port, a pressure responsive bellows element movable in response to change of pressure in said casing and operatively connected to said valve member, a hollow member secured on said casing and overlying said element, a tubular spring abutment member rigid 25 30 with and supported within said hollow member, said abutment member extending into said bellows and having an annular internal shoulder, said hollow member having an expansible-collapsible chamber with a movable wall, a thrust member extending through said tubular member and operatively connecting said wall and said element, said thrust member having a shoulder, and a helical coil spring within said tubular member and surrounding said thrust member, 35 40 said spring being held under compression between said shoulders and opposing expansion of said chamber.
10. A device of the character described, comprising a valve casing having an open side and having an inlet and an outlet, a valve member reciprocable in and controlling flow through said casing, a metal bellows having one end secured to said casing and having a head closing and sealing its other end, means for transmitting movement from said head to said valve member, a hollow member on said casing, a tubular spring abutment member within said hollow member and having a laterally extending supporting flange, said abutment member extending into said bellows and having an internal annular shoulder adjacent said head, a metal bellows within said hollow member and spaced from the side walls thereof, said second-named bellows having oppositely positioned heads, a rigid thrust member 45 50 55 60 65 70 75 extending through said tubular abutment member and having one end engaging said first-named head and having its other end engaging one of said oppositely positioned heads, a bulb element communicating with the interior of said second-named bellows, and a helical coil spring within said tubular member and surrounding said thrust member, said spring having one end seated on said shoulder and having its other end acting on said thrust member to oppose expansion of said second-named bellows.
11. A device of the character described, comprising a valve casing having an open side and having an inlet and an outlet, a valve member reciprocable in and controlling flow through said casing, a metal bellows having one end hermeti- 75 cally secured and sealed to said casing and having a head closing and sealing its other end, means for transmitting movement from said head to said valve member, a hollow member surrounding the open side of said casing and having screw-threaded engagement therewith, a tubular spring abutment member within said hollow member and having a laterally extending supporting flange, said abutment member extending into said bellows and having an internal annular shoulder 10 15 20 25 30 35 40 45 50 55 60 65 70 75 adjacent said head, a metal bellows within said hollow member and spaced from the side walls thereof, said second-named bellows having oppositely positioned heads, a rigid thrust member extending through said tubular abutment member and having one end engaging said first-named head and having its other end engaging one of said oppositely positioned heads, adjustment means carried by said hollow member and cooperable with other of said oppositely positioned heads to regulate the expansion of said second-named bellows, a bulb element communicating with the interior of said second-named bellows, and a helical coil spring within said tubular member and surrounding said thrust member, said spring having one end seated on said shoulder and having its other end acting on said thrust member to oppose expansion of said second-named bellows. 20 25 30 35 40 45 50 55 60 65 70 75
12. In a thermostatic valve including a valve casing, a valve in said casing, a projecting portion, a sealing bellows supported by said portion, and means extending from said bellows to said valve, an actuating element mounted on said casing and said portion, said element comprising a housing snugly fitting said projecting portion, a wall disposed transversely of said housing dividing the same into two chambers, said wall being formed with an aperture at the center thereof, an actuating pin positioned in said aperture; 40 said pin extending into said sealing bellows to operate the same, a power bellows mounted in said housing and in the other chamber thereof, one end of said power bellows being in contact with the opposite end of said actuating pin, and means extending through the end of said housing opposite said sealing bellows for adjusting said power bellows. 45 50 55 60 65 70 75
13. A refrigerant control device comprising a valve body having a passageway therethrough, a valve in said body and controlling flow through said passageway, said body having an open side, a bellows member closing and sealing said side, means operatively connecting said valve to said bellows member for operation thereby, a housing secured to said body and enclosing said bellows member and said open side, a thermostatic bellows member in said housing and responsive to temperature conditions, a supporting member in said housing and positioned between said bellows members, said supporting member having a tubular central portion terminating in an internal shoulder adjacent the head of said sealing bellows member, a thrust member in and extending through said tubular portion and having its ends 65 70 75 engaging said bellows members to transmit movement therebetween, said thrust member having a lateral shoulder facing said internal shoulder, and a spring in said tubular portion and held under compression between said shoulders and urging said thrust member toward said thermostatic bellows member. 75
14. A refrigerant control device comprising a valve body having a passageway therethrough, a valve in said body and controlling flow through 75

- said passageway, said body having an open side, a bellows member closing and sealing said side, means operatively connecting said valve to said bellows member for operation thereby, a housing 5 secured to said body and enclosing said bellows member and said open side, a thermostatic bellows member in said housing and responsive to temperature conditions, a supporting member in said housing and positioned between said bellows members, said supporting member having a tubular central portion terminating in an internal shoulder adjacent the head of said sealing bellows member, a thrust member in and extending through said tubular portion and having its ends 10 engaging said bellows members to transmit movement therebetween, said thrust member having a lateral shoulder facing said internal shoulder, a spring in said tubular portion and held under compression between said shoulders 15 and urging said thrust member toward said thermostatic bellows member, and an adjustment means carried by said housing and operable to regulate the response of said thermostatic bellows member.
- 25 15. A device of the character described, comprising a valve casing having an open side and having an inlet and an outlet, a valve member reciprocal in and controlling flow through said casing, a metal bellows element providing a closure for the open side of said casing and having one end secured to said casing at the margin of said opening and having a closed head sealing its other end, means for transmitting movement from said head to said valve member, a hollow 30 valve casing extension having its inner end open and detachably connected to the valve casing at the margin of its said open side and closed at its opposite end except for a guide passage therethrough, a second metal bellows element within 35 said casing extension adjacent the outer end of the latter and having an outer end head with a tubular extension, said tubular extension being adjustably received in said guide passage, said 40 second bellows element having a closed inner end head opposed to said first-named head, an external thermo-responsive bulb, a conduit connection between said bulb and the interior of said second bellows element and passing through said tubular extension, said casing extension comprising a partition means between the two bellows elements and separable from the portion of the casing extension enclosing said second bellows element, said partition means comprising a cup-shaped portion extending into the first mentioned bellows element and formed with an aperture at its bottom, a thrust member extending through said cup portion and into engagement with the opposed heads of said bellows elements and having a lateral surrounding flange adjacent the top of said cup portion, and a helical coil spring surrounding said thrust member and acting between said flange and the bottom of said cup portion to exert resilient force on the closed inner head 10 of said second bellows element opposing the expansion of the latter.
16. In a refrigerant control device, a body, a valve therein, a sealing bellows supported by the body and operable to actuate said valve, a thermostatic bellows responsive to temperature conditions, a housing secured to the body and enclosing both of said bellows, a wall structure in the housing providing a heat insulating partition between the two bellows and having an axially elongated passageway therethrough, said wall structure having an abutment in said passageway adjacent the sealing bellows, a plunger extending through said passageway and connecting the two bellows and having a lateral spring abutment adjacent the thermostatic bellows, a spring in said passageway and acting between said abutments to urge said plunger toward said thermostatic bellows, and adjustable means on said housing for compressing the thermostatic bellows 25 against the resistance of said spring pressed plunger.

EARNEST J. DILLMAN.
